DISPLAY DEVICE

Albert Everett Goodhue, Quincy, Mass.

Application February 8, 1938, Serial No. 189,467

2 Claims. (Cl. 211—37)

The present invention relates to new and useful improvements in display devices particularly for shoes and has for its primary object to provide, in a manner as hereinafter set forth, a device of 5 this character embodying a novel construction, combination and arrangement of parts through the medium of which a shoe may be supported and displayed on a counter or in a store window in a most advantageous manner.

10 Other objects of the invention are to provide a shoe support of the aforementioned character which will be comparatively simple in construction, strong, durable, highly efficient and reliable in use, compact, light in weight, and which may 15 be manufactured at low cost.

All of the foregoing and still further objects and advantages of the invention will become apparent from a study of the following specification, taken in connection with the accompanying 20 drawing wherein like characters of reference designate corresponding parts throughout the several views, and wherein:

Figure 1 is a side elevational view of my invention showing a shoe supported thereon.

25 Figure 2 is a top plan view of the invention.

Figure 3 is a fragmentary view of the invention with one of the resilient knobs shown in vertical transverse section.

Referring now to the drawing in detail, it will 30 be seen that the reference numeral 5 designates generally a length of wire rod, or other suitable material, bent intermediate its ends as shown at 6 to form a pair of diverging lateral arms 7. The outer end portions of the arms 7 are bent substantially at right angles to the arms 7 to form 35 posts 8.

Knobs 9 formed of rubber or other suitable resilient material are mounted on the upper end portions of the posts 8, and are adapted to contact the sides of the heel 10 of the shoe 11 when the device is in use.

The operation of the device is believed to be manifest but may be briefly described as follows:

The device is placed on the floor of a show 45 window, top of a counter or other level surface with the posts 8 pointing upwardly. The shoe 11

is then rested on the diverging arms 7 with the heel 10 positioned between the knobs 9 in such a manner as to support the shoe with the toe of same pointing upward.

Although I have shown and described herein a preferred embodiment of my invention, it is to be definitely understood that I do not desire to limit the application of the invention thereto, and any change or changes may be made in the materials and in the structure and arrangement of the 10 parts within the spirit of the invention as claimed.

What is claimed is:

1. A shoe support of the character described comprising a length of wire rod bent intermediate its ends to form a V-shaped base, having a 15 curved end portion and substantially straight diverging side portions connected by said curved end portion, a pair of vertical upstanding posts integral with and extending at right angles from the ends of said straight diverging side portions 20 for bracing and holding a shoe in supported position on said base, and resilient anti-scoring knobs mounted on the top ends of said posts in spaced relation to said base.

2. A quick applicable and removable attachment for cleverly balancing and skillfully displaying a conventional shoe so that it may be observed from various angles while assuming a substantially perpendicular position comprising a relatively short resilient partially concealable V-shaped base frame having diverging rectilinear limbs adapted to rest coextensively in direct contact with a flat supporting stationary surface, said frame being of an overall length less than the combined height of the shoe heel and superposed heel portion of the upper so that the latter impinges upon and projects well beyond the vertex of said frame, the spread of the limbs being such that the major part of the frame is virtually concealed from the eye of the observer, the free 30 flexing ends of said limbs having right angularly bent upstanding extensions movable toward and from each other, said extensions constituting heel embracing clamps and terminating in rubber anti-slipping knobs functioning as adjustable grips. 35 40 45

ALBERT EVERETT GOODHUE.
